FURNACE

William Ryan, Chicago, Ill.

Application February 19, 1941, Serial No. 379,590

4 Claims. (Cl. 110—52)

This invention relates to improvements in furnaces and in particular to such improvements which materially increase the efficiency of the furnace.

In furnaces of conventional design the gases of combustion are transferred immediately from the combustion zone to the heating zone where-in they give up by heat exchange their contained heat and are immediately expelled to the atmosphere. The gases from the combustion zone contain a substantial proportion of unburned constituents which are passed out unchanged through the flues and stack and thereby decrease the efficiency of the furnace.

It is therefore the object of my invention to provide a furnace which will permit the maximum fuel utilization and which will give increased fuel efficiency.

It is a further object of my invention to provide a furnace which will permit the recirculation of the gases of combustion to the combustion zone until all of the combustible constituents thereof are substantially completely utilized before the same are passed to the atmosphere.

Other objects of my invention will become apparent from my description thereof read in conjunction with the accompanying drawing which forms a part of this specification and which is a sectional elevation of an embodiment of my invention.

I have discovered that substantially complete fuel utilization can be attained mixing the gases of combustion with air and recirculating the mixture together with additional air and steam into the combustion zone and impinge the total mixture onto a heated surface, such as a baffle. When the mixture of recirculated combustion gases, air and steam contact the heated baffle substantially complete combustion of the unburned gases in the recirculated gases of combustion is effected.

A means of carrying out my invention is illustrated by the following description of a preferred embodiment thereof. The single figure 45 is a longitudinal section through a furnace embodying my invention.

Referring to the drawing, a furnace 10 is provided with a fire door 11, a suitable grate 12, and a clean-out or ash door 13. The furnace 50 is provided with a jacket 14 adapted to receive a heat transfer medium, such as water, having a valved line inlet 15 and a valved line outlet 16. A hollow partition 17 extending transversely across the upper portion of the furnace and 55

communicating with the jacket 14 forms, with the top of the furnace 18, a mixing chamber 19. The furnace is provided at the rear thereof and in the upper portion of the combustion zone 20 with a stack 21, provided with suitable damping means 22.

The mixing chamber 19 communicates with the combustion zone 20 through an opening 23 in the forward portion thereof, and through the conduit 24 in the rear portion thereof, extending upwardly into the mixing chamber 19, and downwardly into the combustion zone 20 to a point below the stack 21.

A valved conduit 25 extends downwardly through the opening 23 to a point in the combustion zone 20 slightly below the partition 17 which provides means for introducing air or other oxygen-containing gases into the combustion zone 20. Concentric with the conduit 25, a steam pipe 26, provided with suitable valve means 27, directs steam into the conduit 25.

Located in the combustion zone 20 directly beneath the conduit 25 is a baffle 28 provided with a plurality of openings 29, and suspended 25 by suitable adjustable suspension means 30, adjustable from the exterior of the furnace, such as by a cam lever. The baffle 28 is fabricated of heat resistant material, preferably fire-brick or similar heat resistant ceramic material.

A valved conduit 31, extends into the mixing chamber 19 to the rear portion thereof, and provides a means of introducing air or other oxygen-containing gases into the mixing chamber 19.

The advantages of employing a furnace embodying my above-described invention may be readily comprehended from the following description of the operation and function thereof.

Hot gases resulting from the combustion of 40 the fuel in the combustion zone 20, rise in the combustion zone 20 and ascend through the conduit 24 into the mixing chamber 19 wherein it is commingled with air introduced through the conduit 31. As the hot gases in the mixing chamber 19 give up some of their heat to the body of water in the adjacent jacket 14 and the jacket forming the partition 17, the cool air-gas mixture descends to the combustion zone 20 through the passageway 23.

Air, introduced through the conduit 25, and steam, introduced through the steam line 26, are admixed with the recirculating gas-air mixture from the mixing chamber 19. The steam may be that from any source and may be taken directly from the furnace after sufficient steam,

has been generated. The admixture of air, steam, and recirculating gases of combustion impinge upon the hot perforated baffle 29, and the unburned constituents of the recirculated combustion gases burned. The baffle 29 attains a temperature sufficient to cause substantially complete combustion of the recirculating gases. To obtain the highest efficiency from the baffle 29, the same may be lowered or raised, as required, by means of a cam lever operating the suspension means 30.

A small portion of the gases from the combustion zone pass up the stack 21. These gases are substantially completely consumed gases, so that substantially no smoke is emitted from the stack 21. The volume of gases permitted to escape up the stack 21 may be controlled by the damper 22.

My invention materially increases the efficiency of the furnace and provides greater fuel economy, since by the recycling of the hot gases from the combustion zone to the mixing zone and back to the combustion zone admixed with oxygen and/or an oxygen-containing gas and steam, I obtain substantially complete utilization of the gases of combustion which would otherwise pass up the stack and not be utilized for useful heating. By providing a baffle, such as baffle 29, in the combustion zone, upon which the returning gases may impinge and be substantially completely combusted, I avoid the necessity of returning those gases to the fire pot, where they would become ignited and raise the temperature adjacent the fire grate to a point where it is burned out.

While I have shown in a preferred embodiment of my invention a furnace in which the mixing chamber is an integral part of the same, I may modify the described arrangement by providing a mixing chamber external of, but adjacent to the furnace structure, such as a mixing chamber superimposed upon the furnace proper.

While I have illustrated and described certain particular embodiments of my invention, I do not wish to be understood as intending to limit the

same thereto, as the same may be variously modified and altered without departing from the spirit of the invention, which is defined by the following claims.

5 I claim:

1. In a furnace, the combination with a combustion zone adapted to be occupied by hot gases of combustion produced by the ignition of fuel in said furnace, a stack, a mixing chamber, spaced conduits opening at their upper ends in said mixing chamber and at their lower ends into said combustion zone, the upper end of said conduits extending into the mixing chamber above the upper end of the other conduit, and the 10 lower end thereof extending into the combustion zone below the stack, means for introducing air into the mixing chamber, means for introducing air and steam into the admixed air and gases of combustion from the combustion zone, and a baffle in the combustion zone located below the 15 conduit conducting gases from the mixing chamber to the combustion zone.

2. In a furnace as described in claim 1 in which the baffle is vertically adjustable.

25 3. In a furnace, the combustion with a combustion zone adapted to be occupied by hot gases of combustion produced by the ignition of fuel in said furnace, a mixing chamber, a stack, a conduit extending into the mixing chamber to the upper portion thereof, and extending into the combustion zone to a point below the stack, a second conduit spaced from said first conduit, extending into the mixing chamber to a point below the upper end of said first conduit, and 30 extending into the combustion zone to a point above the lower end of said first conduit, means for introducing air into said mixing chamber, means for introducing air and steam into said second conduit, and a fire resistant baffle suspended in the combustion zone at a point immediately below said second conduit.

35 4. In a furnace as described in claim 3 in which the fire resistant baffle is vertically adjustable.

WILLIAM RYAN.
